(57) **CLAIM**

We claim the ornamental design for a television receiver, as shown and described.

DESCRIPTION

FIG. 1 is a front perspective view of a television receiver showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a bottom front perspective view thereof;
FIG. 9 is a rear perspective view thereof;
FIG. 10 is an enlarged view of the encircled portion in FIG. 1;
FIG. 11 is an enlarged view of the encircled portion in FIG. 2;
FIG. 12 is an enlarged view of the encircled portion in FIG. 8;
FIG. 13 is an enlarged view of the encircled portion in FIG. 5; and,
FIG. 14 is an enlarged view of the encircled portion in FIG. 9.

The dash-dash broken lines in the figures depict portions of the television receiver that form no part of the claimed design.

The dot-dash broken lines in the figures represent a boundary line and form no part of the claimed design.

(Continued)

The dot-dot-dash broken lines encircling portions of the claimed design that are illustrated in enlargements form no part of the claimed design.

The unshaded surface in the figures that directly adjoins the claimed solid line edge forms no part of the claimed design.

1 Claim, 12 Drawing Sheets
